UNITED STATES PATENT OFFICE.

RUSSELL H. WILHELM, OF EASTON, PENNSYLVANIA, ASSIGNOR TO INGERSOLL-BAND COMPANY, OF JERSEY CITY, NEW JERSEY, A CORPORATION OF NEW JERSEY.

STEEL-RETAINER FOR HAMMER-DRILLS.

1,217,378.

Specification of Letters Patent. Patented Feb. 27, 1917.

Application filed July 21, 1916. Serial No. 110,461.

To all whom it may concern:

Be it known that I, RUSSELL H. WILHELM, a citizen of the United States, residing at Easton, in the county of Northampton and State of Pennsylvania, have invented a certain new and useful Improvement in Steel-Retainers for Hammer-Drills, of which the following is a specification.

This invention relates to steel retaining mechanism for hammer drills.

On hammer drills, particularly of the hand type, it is necessary to provide a device which can be utilized to engage the drill steel to move it with the drill when it is desired to remove the steel from or loosen it in the drilled hole. In drills of the type in question the steel is usually of a uniform cross section, except that it is provided with a collar which abuts against the forward end of the front head of the drill and determines the position of the steel therein. Various devices have been devised to engage and hold the drill steel when desired these generally consisting of a yoke pivoted in some way on the front head of the drill and arranged to be held more or less firmly in contact with the steel during the operation of the drill, but so arranged as to be capable of being moved out of contact with the drill steel so that the steel can be removed from the front head of the drill.

The object of the present invention is to provide a simple and effective steel retaining device of this type which will be effectively maintained in operative position during the operation of the machine and which can be easily moved to an inoperative position and retained there without being held.

With this object in view I have devised a steel retaining mechanism, a practical embodiment of which is shown in the accompanying drawings, in which—

Figure 1 shows a plan view of the front head of a drill provided with my steel retaining device in operative position,

Fig. 2, a side elevation of the same, and

Fig. 3, a side elevation showing the steel retaining mechanism in inoperative position.

In the drawings is shown the front head 1 of an ordinary drilling machine, not shown, in which is mounted the drill steel 2 provided with a collar 3 which abuts against the front end of the front head 1 and determines the position of the steel therein. On the lower side of the front head 1, out of alignment with the steel 2, are oppositely placed lugs 4 projecting from the front head these being of cylindrical contour on their forward sides 5 but being flattened on their rear faces to produce flat surfaces 6. Pivoted on these lugs is the steel retaining mechanism, which consists of a yoke 7 having an upwardly projecting portion 8 provided with a slot 9 adapted to fit over the steel 2 but not sufficiently wide to permit passage therethrough of the collar 3. Projecting rearwardly from the offset portion 8 of the yoke are side arms 10 which are provided at their rearward ends with heads 11, the rearward faces of the heads 11 being provided with semi-circular depressions 12 adapted to fit and rotate on the forward rounded sides 5 of the lugs 4. Sliding in bores 13 passing through the upper portions of the heads 11 are retaining bolts 14, the heads 15 of which project downwardly and are provided on their forward sides with flat surfaces 16 adapted to contact with the flat surfaces 6 of the lugs 4 when the steel retaining mechanism is in its operative position as shown in Fig. 2. The forward ends of bolts 14 are provided with nuts 17 and springs 18 are interposed between the nuts 17 and the forward sides of the yoke side arm heads 11 so that there is a constant resilient pressure tending to force heads 11 of the side arms 10 and heads 15 of the retaining bolts 14 together.

The operation of the present device will be easily understood from the above description. When the drill is in operation the steel retaining device is moved into the position shown in Fig. 2 and held there by reason of the contact of the flat surfaces 6 and 16 of the lugs 4 and the steel retaining mechanism. When it is desired to remove the steel from the drill the yoke 7 is grasped by the hand of the operator and moved to the position shown in Fig. 3, in which position the flat surfaces 16 are in contact with the rounded surfaces of the lug 4 and have no tendency to move the steel retaining mechanism into operative position so that the steel retaining mechanism will remain in this position until moved into operative position again by hand.

It is to be understood that while the present showing and description discloses only one specified modification of this invention, other forms and modifications are included.

within the spirit and scope thereof, as expressed in the appended claims.

What I claim is:

1. In combination with a drilling tool having a front head and a collared drill steel, operatively mounted in said front head, lugs on opposite sides of said front head, and a steel retaining mechanism trunnioned on said lugs, said steel retaining mechanism comprising a yoke having a steel engaging slot and side arms contacting with and bearing on the forward sides of said lugs, retaining bolts slidably mounted in said side arms and having portions engaging the rear sides of said lugs, and means for resiliently drawing said yoke and retaining bolts together.
2. In combination with a drilling tool having a front head and a collared drill steel operatively mounted in said front head, lugs on opposite sides of said front head, and a steel retaining mechanism trunnioned on said lugs, said steel retaining mechanism comprising a yoke having a steel engaging slot and side arms contacting with and bearing on the forward sides of said lugs, retaining bolts slidably mounted in said side arms and having portions engaging the rear sides of said lugs, and means for resiliently drawing said yoke and retaining bolts together.

sides of said lugs, means for resiliently drawing said yoke and retaining bolts together and means for holding said yoke in operative position.

3. In combination with a drilling tool having a front head and a collared drill steel operatively mounted in said front head, lugs on opposite sides of said front head, and a steel retaining mechanism trunnioned on said lugs, said steel retaining mechanism comprising a yoke having a steel engaging slot and side arms contacting with and bearing on the forward sides of said lugs, retaining bolts slidably mounted in said side arms and having portions engaging the rear sides of said lugs, means for resiliently drawing said yoke and retaining bolts together and means for holding said yoke in operative position comprising flattened surfaces on said lugs arranged to contact with surfaces on said steel retaining mechanism when said yoke is in operative position.

In testimony whereof, I have hereunto set my hand.

RUSSELL H. WILHELM.
